UNITED STATES PATENT OFFICE.

STACY B. HASELTINE, OF CHICAGO, ILLINOIS, ASSIGNOR TO WILLIAM H. MINER, OF CHAZY, NEW YORK.

FRICITION-GEAR.

1,258,897.

Specification of Letters Patent. Patented Mar. 12, 1918.

Application filed May 10, 1915. Serial No. 27,005.

To all whom it may concern:

Be it known that I, STACY B. HASELTINE, a citizen of the United States, residing at Chicago, in the county of Cook and State of Illinois, have invented a certain new and useful Improvement in Friction-Gears, of which the following is a full, clear, concise, and exact description, reference being had to the accompanying drawings, forming a part of this specification.

This invention relates to improvements in friction gears.

The object of the invention is to provide a friction gear for railway draft rigging having high capacity, certain release, and so arranged that the pressure from the wedges to the friction shoes is distributed evenly to the latter.

Another object of the invention is to provide an arrangement of wedges, friction shoes and shell wherein anti-friction rollers are employed that extend lengthwise of the gear.

The invention furthermore consists in the improvements in the parts and devices, and in the novel combinations of the parts and devices herein shown, described or claimed.

In the drawing forming a part of this specification, Figure 1 is a longitudinal vertical sectional view of a draft rigging showing my improvements in connection therewith. Fig. 2 is an enlarged view of the friction shell and coöperating wedges and shoes showing the parts in full compression.

Fig. 3 is an end elevation of the friction gear with the outer wedge block removed, the bolt being shown in section. Fig. 4 is a sectional view taken on the line 4—4 of Fig. 2. Fig. 5 is a detailed view of the combined inner wedge block and spring follower. Fig. 6 is a detailed perspective view of one of the friction shoes, and Fig. 7 is a detailed perspective view of one of the secondary or auxiliary members.

In said drawing, 10 denotes the center or draft sill of a railway car to which are secured the rear and front stops 11 and 12. The draw-bar 13 is keyed to a hooded cast yoke 14 in the usual manner, the parts being supported as shown, by a saddle plate 15.

The friction gear proper is designated generally by the reference letter A, and as shown, comprises a combined friction shell and cylinder 16 having an integral rear wall 17, which acts as a rear follower, the wall

17 being provided with a hollow inwardly extending boss 18. Coöperating with the friction shell proper, are a plurality of circularly arranged friction shoes 19 each of which has an exterior curved friction surface 20, coöperating with the corresponding curved internal friction surface of the shell.

Each shoe is also provided at its end with an inwardly extending rib or flange 21 for a purpose hereinafter described. On their inner faces the shoes are also provided with a pair of longitudinally extending wedging faces 22—22, one near each edge of the shoe. For spreading the shoes and thereby creating friction, I have provided an outer wedge block 23, an inner combined wedge block and spring follower 24, and a plurality of longitudinally arranged auxiliary or secondary wedge members 25—25, the latter corresponding in number to the number of friction shoes. Each of the wedging elements 25 is provided with beveled wedging ends 26 and 27 coöperating respectively with the beveled wedging ends 28 and 29 of the outer and inner wedge blocks 23 and 24.

Each wedging element 25 is also provided with a pair of longitudinally extending wedging faces 30—30 on their outer sides disposed opposite the corresponding wedging faces 22—22 of two adjacent friction shoes. Interposed between each wedge member 25 and two friction shoes, are longitudinally extending anti-friction rollers 31—31, the latter being held in proper position by means of shoulders 32—32 on the corresponding wedge members 25. The wedge members 25 are normally spaced slightly apart, as clearly indicated in the various figures of the drawing, and the same are also suitably recessed along their inner faces as indicated at 33 to provide clearance for the connecting or tension bolt 34 which passes therebetween and through the wedge blocks 23 and 24 and the boss 18. The inner combined wedge block and spring follower 24 is provided with an annular extending groove 35 into which fit the flanges or shoulders 21 of the friction shoes. The wedge block 24 is also provided with an annular flange 36 engaging the inner ends of the friction shoes, the construction thus described serving to lock the friction shoes and inner wedge block together so that the same will always move substantially simultaneously inwardly or outwardly. For re-

sisting movement of the friction elements, I have provided a main spring which in the form shown, comprises an outer heavy coil 37 and a nested inner coil 38.

5 The operation is as follows: Upon pressure applied to the outer wedge block 23 from the front follower 39, the secondary wedge members 25 will be forced outwardly or radially of the gear, their longitudinal movement relatively to the friction shoes being prevented because of the fact that the inner wedge block 24 cannot be displaced in this direction. The outward or radial movement of the wedge members 25 in turn 10 presses the friction shoes outwardly or radially, the tendency being to enlarge the circle formed by the outer faces of the friction shoes. In this movement, it will be apparent that the outward thrust against 15 the shoes from the wedge members 25 is distributed to the shoes over a relatively large area, that is, over the entire length of the anti-friction rollers 31 proper. As the pressure is applied to the wedges and inward 20 movement is resisted by the spring, the pressure of the friction shoes against the friction shell is gradually increased. Upon release, it is evident that the set of auxiliary wedge members 25 will collapse and thereby relieve 25 the pressure between the friction shoes and the shell so that the expansion of the main spring will force all the parts outwardly.

From the foregoing description it will be seen that with my arrangement I am enabled 30 to employ relatively blunt angles between the wedge blocks 23 and 24 and the ends of the secondary wedges 25, thus insuring certain release and at the same time am enabled to use relatively acute or sharp angles between the wedging faces of the members 25 35 and friction shoes, thereby creating an immense pressure.

Although I have herein shown and described in detail one embodiment of my invention, yet I do not wish to be limited to the exact construction shown inasmuch as I believe it to be broadly new to employ anti-friction rollers arranged longitudinally of the shell or with the axes of the rollers substantially parallel with the center line of the gear, and I desire to claim the same broadly and contemplate all changes and modifications that come within the scope of the claims appended hereto.

55 I claim:

1. A friction gear comprising a friction shell, friction shoes coöperable therewith, a spring, a plurality of wedging members co-operating with said shoes, and anti-friction rollers interposed between some of said wedging members and said shoes, the axes of said rollers extending parallel to the axis of the shell.

2. A frictional shock absorbing mechanism comprising a friction shell, friction

shoes coöperable therewith, a spring, a plurality of wedging members coöperable with the shoes, and a plurality of anti-friction rollers arranged lengthwise of the shoes and interposed therebetween and some of said wedging members.

3. A friction gear comprising a friction shell, friction shoes coöperable therewith, a spring, a plurality of wedge members within the shoes and arranged to move radially of the shell to force the friction shoes outwardly, a spring follower engaging the inner ends of said wedge members, a wedge block engaging the outer ends of said wedge members, and coöperable, interlocking means on said shoes and spring follower arranged to prevent independent longitudinal movement of the spring follower and shoes.

4. A friction gear comprising a friction shell, friction shoes, a spring, outer and inner wedge blocks, secondary wedge members between said blocks and said shoes, and means preventing relative longitudinal movement between the inner wedge block and said shoes.

5. A friction gear comprising a friction shell, friction shoes, a spring, outer and inner wedge blocks, secondary wedge members between said blocks and said shoes, and means preventing relative longitudinal movement between the inner wedge block and said shoes, said means including interfitting grooves and flanges.

6. A friction gear comprising, a friction shell, a plurality of friction shoes coöperable therewith, a spring, a spring follower at the inner end of said shoes and having wedge surfaces, a plurality of longitudinally arranged wedge members located within the shoes and coöperable therewith, and also with the wedge surfaces of said spring follower, and an outer wedge block coöperable with the outer ends of said wedge members and arranged to spread the same radially.

7. A friction gear comprising a friction shell, friction shoes, a spring, inner and outer wedge blocks, a plurality of wedge members within said shoes and interposed between said blocks and coöperable therewith and a plurality of anti-friction rolls extending lengthwise of the shoes and interposed therebetween and said wedge members.

8. A friction gear comprising a friction shell, friction shoes, an outer wedge block, a plurality of longitudinally arranged wedge members disposed within the shoes, an inner wedge block coöperable with said wedge members, and interfitting means on said inner wedge block and said shoes, arranged to cause the inner wedge block and shoes to move simultaneously.

9. A friction gear comprising a friction shell, a plurality of circularly arranged friction shoes within said shell, said shoes each

- having a pair of oppositely arranged, longitudinally extending wedge faces on their inner sides, a spring, a plurality of wedge members located within said shoes and having each a pair of longitudinally extending wedge faces, and means for spreading said wedge members radially when the gear is actuated.
10. A friction gear comprising, a friction shell, friction shoes, a spring, inner and outer wedge blocks, a plurality of wedge members interposed between said blocks, said wedge members and friction shoes having coöperating longitudinally extending wedging faces and a plurality of anti-friction elements interposed between said wedging faces.
11. A friction gear comprising a friction shell, friction shoes, a spring, inner and outer wedge blocks, the inner block also serving as a follower for said spring, a plurality of wedge members interposed between said blocks and coöperable therewith, and a plurality of anti-friction rollers interposed between said wedge members and said shoes, the axes of said rollers extending substantially parallel with the center line of the gear.

In witness that I claim the foregoing I have hereunto subscribed my name this 28th day of April 1915.

STACY B. HASELTINE.
